[57] CLAIM

The ornamental design for playing card holder, as shown.

DESCRIPTION

FIG. 1 is a right hand perspective view of the playing card holder;

FIG. 2 is an end view (both right hand & left hand end views are the same) thereof;

FIG. 3 is a front view thereof;

FIG. 4 is a top view thereof;

FIG. 5 is a bottom view thereof; and,

FIG. 6 is a rear view thereof.

The broken line showing of the playing cards is for illustrative purposes only, and forms no part of the claimed design.

[] Term: 14 Years

[21] Appl. No.: 899,928

[22] Filed: Jun. 17, 1992

[52] U.S. Cl. D21/54; D21/57

[58] Field of Search 273/236-285,
273/148 A, 150; D21/48, 54-57
